(57) **ABSTRACT**

A body structure for a rail vehicle that includes a frame with at least one support element made at least predominantly of steel alloy, at least one equipment element made predominantly of aluminum alloy, at least one first plate having at least one longitudinal edge and a first surface delimited by the longitudinal edge, and at least one longitudinal batten of steel alloy, which is integral with the support element, wherein the longitudinal batten is fixed flat to the first face by way of friction melt bonding.

**RAILWAY VEHICLE BODY STRUCTURE
AND MANUFACTURING PROCESS
THEREOF**

BACKGROUND OF THE INVENTION

Field of the Invention

The present invention relates to a body structure for a railway vehicle and a method for manufacturing such a body structure.

Description of the Related Art

To make a body structure of a railway vehicle, such as a carriage or a wagon, it is known to assemble elements made of different metallic materials in order to optimize the weight of the body. In particular, the floors of the structure may be made of aluminum, while other parts, such as the support trusses of the floors, are made of steel. In order to ensure the solidity and the longevity of the structure, it is preferable to join together the various elements that compose it by welding. However, welding steel elements to aluminum elements requires special precautions, insofar as these materials are difficult to weld together and tend to generate galvanic corrosion when they are brought into contact with each other.

FR-A1-2 630 698 discloses a vehicle, provided with a body, the structure of which comprises two floor levels formed by plates of extruded aluminum, and faces consisting of vertical uprights and steel stringers designed to support these two floor levels. Composite elements are provided to enable the fixing of the floors to the faces. Each of these composite elements comprises an aluminum part, which is welded to one of the floors, and a steel part, which is welded to one of the steel faces.

In order to manufacture the composite elements, it is known to attach the aluminum part and the steel part by means of fastening elements (bolt, rivet, etc.) or by means of explosion welding, which may be expensive and complex. Moreover, because of its particular mode of implementation, this explosion welding is generally carried out in advance, separately from the other assembly steps of the structure. To this must be added the need to weld the composite element to the floors, with an aluminum-to-aluminum weld, and to the faces, with a steel-to-steel weld. As a result, a total of three different welding technologies is required to assemble the aluminum floors with the steel faces.

SUMMARY OF THE INVENTION

Accordingly, the invention aims to remedy the aforementioned disadvantages of the prior art and proposes a new body structure whose manufacture is easier and cheaper, while this new body structure is no less solid and durable than known structures.

The object of the invention is a body structure for a railway vehicle, the body structure of which comprises:

a frame, which comprises at least one support element made at least predominantly of steel alloy, and at least one equipment element made predominantly at least of aluminum alloy, which comprises at least one first plate having at least one longitudinal edge, and a first face delimited by the longitudinal edge.

According to the invention, the body structure further comprises at least one longitudinal batten made of a steel

2

alloy, which is integral with the support element, wherein the longitudinal batten is fixed flat on the first face by means of a friction melt bonding.

According to the invention, the equipment element is fixed to the support element by means of a minimum number of intermediate pieces and welds. Friction melt bonding, which is a recent and efficient technique described for example in EP A 2 844 415, may be advantageously directly implemented during the manufacture of the body structure of the invention. In fact, this friction melt bonding may be carried out by applying a rotating friction melt bonding tool to a free face of the longitudinal batten, wherein the free face is opposite to a face supported against the first face. The friction melt bonding is thus carried out by conduction through the longitudinal metal batten to fix the latter to the equipment element situated underneath. The body structure so obtained is particularly strong, durable and inexpensive.

According to other advantageous features of the invention, taken singly or in combination:

10 A longitudinal flat spot is provided in the first face, on only part of this first face extending from the longitudinal edge, wherein the longitudinal batten is fixed on the equipment element flat against the longitudinal flat spot.

15 Two plates are provided, wherein the first plate comprises a second face opposite the first face and a second plate parallel to the first plate, and wherein the equipment element comprises a longitudinal web which projects from a lateral part of the second face, wherein the lateral part extends from the longitudinal edge and facing the longitudinal batten, the web connects the first plate to the second plate.

20 The longitudinal batten is integral with the support element and belongs to the latter.

25 The longitudinal batten has a longitudinal outer edge by means of which the longitudinal batten is welded to the support element.

30 The longitudinal batten has an extra thick portion which extends from the longitudinal outer edge.

35 The longitudinal batten has a chamfered longitudinal inner edge, wherein the body structure comprises a sealing gasket applied against the longitudinal inner edge.

40 The support element forms a truss while the equipment element forms a floor.

45 The object of the invention is also to provide a method for manufacturing a body structure according to the above description, wherein this manufacturing method comprises the step of fixing the longitudinal batten on the first face by means of friction melt bonding through the longitudinal batten by applying a rotating friction melt bonding tool to a free face of the longitudinal batten, wherein the free face lies opposite a support face of the longitudinal batten against the first face.

50 Finally, according to another advantageous characteristic of the invention, the friction melt bonding tool is applied to the free face facing the first face, while projecting beyond the longitudinal edge.

BRIEF DESCRIPTION OF THE DRAWINGS

The invention will be better understood by reading the description which follows, given solely in the form of a non-limitative and non-exhaustive example and made with reference to the drawings, wherein:

55 FIG. 1 shows a partial cross-section of a body structure according to a first embodiment of the invention;

FIG. 2 shows a view on a larger scale of the detail II in FIG. 1, and

FIG. 3 shows a partial cross-section of a body structure according to a second embodiment of the invention.

DESCRIPTION OF THE PREFERRED EMBODIMENTS

In the following, the sectional plane of FIGS. 1 to 3 is referred to as a "transverse plane", so that the terms "longitudinal" and "length" designate an orthogonal, or at least intersecting, direction with respect to this transverse plane. Moreover, the terms "upper" and "top" refer to an upwardly-directed transverse direction in FIGS. 1 to 3, while the terms "lower" and "bottom" designate an opposite transverse direction. Finally, the terms "horizontal" and "vertical" respectively designate horizontal and vertical directions under normal conditions of use of the vehicle, when the latter is resting on rails: in this case, the horizontal direction is represented horizontally in the figures, while the vertical direction is shown vertically.

The structure 1 of FIGS. 1 and 2 belongs to a body of a rail vehicle, of the wagon, carriage or locomotive type, intended, for example, to form a part of the composition of a train.

The term "body" refers to the upper part of the vehicle, resting on bogies of the vehicle. The body is intended to contain persons or goods carried by the vehicle or a traction unit in the case of a locomotive. Conventionally, the body comprises at least one horizontal floor 2 and lateral walls 4, only one of which is partially visible in FIG. 1, and which rise from the floor 2 in order to delimit an interior volume V of the body. Alternatively, several floors may be provided to form levels within the body. The body preferably comprises a roof or cover (not shown) enclosing the volume V from above, and featuring inner and outer cladding elements (also not shown). The floor 2, the lateral walls 4 and the roof thus constitute equipment elements of the structure 1.

The structure 1 also comprises a chassis 6, formed predominantly by an assembly of support elements of the beam and truss type. Preferably, most of the support elements are made at least predominantly, or even totally, of steel or of a steel alloy in order to provide the chassis 6 with a predetermined mechanical strength to suit the conditions of use of the vehicle. For the most part, this means that more than 50 wt.-% of each support element is made of steel or a steel alloy. Preferably, at least the majority of the support members form metal profiles. The support members are assembled together by welding, riveting, bolting, or any other suitable technique. The chassis 6, therefore, constitutes a rigid framework, the purpose of which is, in particular, to support the equipment elements, including the floor 2 and the lateral walls 4.

Advantageously, two longitudinal rows of vertical uprights 8 form support elements for the lateral walls 4 of the body.

The frame 6 also includes at least two trusses 10, only one of which is visible in FIGS. 1 and 2, and wherein each forms a longitudinal beam of the frame 6. Each of the trusses 10 connects the vertical uprights 8 of one of the longitudinal rows to one another by being welded to these vertical uprights 8. Each truss 10 is made of steel, or of a steel alloy, at least predominantly, and preferably totally. Each truss 10 is preferably formed by a profile, i.e. a part obtained by extrusion of material, or formed by an assembly of profiled elements fixed to each other. The trusses 10 are arranged at

the same height between the two rows of vertical uprights 8 and form support elements for the floor 2 of the structure 1.

In particular, each truss 10 has a fixing surface 12 that is planar and oriented in a longitudinal plane parallel to the walls 4. Each fixing surface 12 is turned towards the inside of the body, so that the two fixing surfaces 12 face one another.

Each truss 10 also preferably comprises a part 14 shaped to receive a lower end 9 of the vertical uprights 8, opposite the fixing surface 12.

The floor 2 comprises a profile at least predominantly, or even totally, made of aluminum or an aluminum alloy, so that it is particularly easy to manufacture and comprises a small number of parts. By "predominantly" is meant that more than 90 wt.-% of the floor 2 is made of aluminum or of an aluminum alloy.

The floor 2 comprises a first upper horizontal plate 16 and a second lower plate 18 disposed at a distance from and parallel to the plate 16. The plate 16 has an upper face 26 and a lower face 28 opposite each other, while the plate 18 has an upper face 30 and a lower face 32 opposite each other. The plate 16, and, in particular, its faces 26 and 28, end laterally in two longitudinal edges 22, only one of which is visible in FIGS. 1 and 2, with respect to the fixing surface 12, wherein each forms a vertical surface extending in a longitudinal plane and between which the body of the plate 16 extends. Similarly, the plate 18, and in particular its faces 30 and 32, end laterally in two longitudinal edges 24 whose surface extends in the same plane as that of the corresponding longitudinal edges 22 of the plate 16.

Two longitudinal flat spots 34 are formed in the upper face 26, wherein each extends from one of the edges 22 to a longitudinal chamfer 36 of the upper face 26 of the first upper plate 16. In the example of FIG. 2, the chamfer 36 defines an angle α_{36} equal to approximately 35°, wherein the angle α_{36} is measured with respect to a plane parallel to the surface of the edge 22. The upper face 26 also comprises a substantially flat central part 38 delimited by the two chamfers 36. Likewise, two longitudinal flat spots 40 are formed in the bottom face 32 of the second bottom plate 18, wherein each extends from one of the edges 24 to a longitudinal chamfer 42 of the lower face 32. As illustrated in FIG. 2, the chamfer 42 defines an angle α_{42} equal to the value of the angle α_{36} , wherein the angle α_{42} is measured with respect to a vertical plane parallel to the surface of the edge 24. The lower face 32 also comprises a substantially flat central part 44 delimited by the two chamfers 42.

The lower face 28 of the first upper plate 16 comprises a central portion 48 and two lateral portions 46 extending on either side of the central part 48 to the longitudinal edges 22. Each lateral portion 46 extends in a direction opposite to the edge 22, i.e. on the opposite side of one of the flat spots 34, and extends, in a direction opposite to the edge 22, beyond the corresponding flat spot 34. The central part 48 extends in an intermediate plane P48 disposed between an upper plane P38 defined by the central part 38 of the upper face 26, and a flat spot plane P34 defined by the longitudinal flat spot 34. In other words, the depth of the flat spot 34 is greater than the thickness of a central zone delimited by the central portions 38 and 48 of the faces 26 and 28 of the plate 16, which makes it possible to optimize the mass of the floor 2, while giving it a high mechanical resistance. In the example of FIGS. 1 and 2, the vertical distance D38 between the planes P38 and P48 is 2.8 mm, while the vertical distance D34 between the planes P38 and P46 is 4 mm.

The upper face 30 comprises a central portion 50 and two lateral portions 52 extending on either side of the central

portion **50** to the longitudinal edges **24**. Each lateral part **52** lies opposite, i.e. on the opposite side of one of the flat spots **40**, and extends in a direction opposite to the edge **24** beyond the corresponding flat spot **40**. The central portion **50** extends in an intermediate plane **P50** arranged between a lower plane **P44** defined by the central portion **44** of the lower face **32**, and a flat spot plane **P40** defined by the longitudinal flat spot **40**. In other words, the depth of the flat spot **40** is greater than the thickness of a central zone delimited by the central portions **44** and **50** of the faces **30** and **32** of the plate **18**, which makes it possible to optimize the mass of the floor **2** while giving it a high mechanical resistance.

The floor **2** comprises two longitudinal webs **54** disposed close to the longitudinal edges **22** and **24**, and only one of which is visible in FIGS. 1 and 2. Each longitudinal web **54** interconnects the plates **16** and **18**. In particular, each longitudinal web **54** extends in a plane perpendicular to the flat spot planes **P34** and **P40** and projects from the lateral portion **46** of the lower face **28** to the lateral portion **52** facing the upper face **30**. Each longitudinal web **54** thus extends into an intermediate position between a vertical plane **P36** defined by the base of the chamfers **36** and a vertical plane **P22** defined by the edges **22** and **24**. The webs **54** are integral with the plates **16** and **18**.

In a manner known per se, the lower face **28** is connected to the upper face **30** by oblique cladding **20** to stiffen the floor **2** and which is integral with the plates **16** and **18**. The oblique cladding **20** is disposed between the two longitudinal webs **54**. Alternatively, the floor **2** may be devoid of oblique cladding, and instead comprise other stiffening means, or is devoid of stiffening means.

It will be understood that an extreme portion of the floor **2**, including the flat spots **34** and **40**, the web **54**, the edges **22** and **24**, is symmetrical with respect to a plane of symmetry **P2** defined equidistantly from the plates **16** and **18**.

The floor **2** is assembled with the trusses **10** by means of four longitudinal battens of steel alloy, wherein only two battens **56** and **58** are visible in FIGS. 1 and 2. The two longitudinal battens **56** are fixed flat on the flat spots **34**, while the two longitudinal battens **58** are fixed flat on the flat spots **40**, respectively. Each batten **56** and **58** comprises a support face **60** which bears against the flat spots **34** or **40**, and an opposite free face **62**. Each batten **56** and **58** is delimited transversely by a longitudinal internal edge **64** and a longitudinal outer edge **66** ending the faces **60** and **62**. For each batten **56** or **58**, the support face **60** covers the flat spot **34** or **40**, so that the inner edge **64** is in contact with the chamfer **36** or **42** respectively. Each batten **56** or **58** extends beyond the edge **22** or **24** concerned, so that a portion of each batten **56** and **58** projects beyond the floor **2** beyond the plane **P22**.

Each batten **56** and **58** is secured to the floor **2** via its support face **60**, which is welded to the flat spot **34** or **40** and against which it is supported by means of a friction melt bonding **S**. In order to effect this friction melt bonding **S**, a rotating friction melt bonding tool **61** is rotated against the free face **62** of the longitudinal batten **56** or **58** concerned, in order to heat this batten **56** or **58** through friction, so that the frictional heat is transmitted to the floor **2** through the batten **56** or **58** concerned, at the longitudinal flat spot **34** or **40** concerned, which results in the welding of the steel alloy of the batten **56** or **58** with the aluminum alloy of the floor **2**. In practice, the tool **61** is applied against the batten **56** or **58** with a predetermined force **F61**, wherein the force **F61** is directed along an axis **X61** of the tool **61**, and wherein this

axis **X61** is perpendicular to the flat spot **34** or **40** concerned, when the tool **61** is in contact with the batten **56** or **58**. The tool **61** is rotated about the axis **X61**. The tool **61** is moved along the batten **56** or **58**, while being rotated about the axis **X61** and being applied with the force **F61**, in order to create a continuous, or even discontinuous, weld **S**. The presence of the web **54** enables the floor **2** to resist the forces involved during this friction melt bonding **S**. In this case, the web **54** is disposed opposite each batten **56** and **58**, i.e. under, on the other side of the plate **16** or **18** concerned, in order to improve the bending resistance of this plate **16** or **18**. Thus, to effect the weld **S**, the tool **61** is positioned vertically above the web **54**, i.e. in the axis of the latter. In other words, the axis **X61** is aligned with a median plane of the web **54**, as illustrated in FIG. 2.

The tool **61** has one end, applied to the batten **56** or **58**, the shape of which is cylindrical with a circular base about the axis **X61**. It is provided that this end has a diameter $\phi 61$ that is sufficiently high for the contact surface between the tool **61** and the batten **56** or **58** to project beyond the edge **22** or **24** of the flat spot **34** or **40**, in order to ensure that the friction melt bonding **S** extends at least as far as the edge **22** or **24** concerned, or even beyond the edge **22** or **24**, in order to ensure the sealing of the weld **S** at the support face **60**. In other words the tool **61** is crossed by the plane **P22** during the welding **S**. In the example illustrated in FIG. 2:

the width **L65** of the battens **56** and **58**, measured between the edges **64** and **66** parallel to the support face **60**, is 40 mm,

the diameter $\phi 61$ is, for example, between 10 and 25 mm, the tool protrudes 1 to 2 mm from the edge **22**.

It is provided that the battens **56** and **58** are sufficiently thin to facilitate heat transmission to the floor **2** during the friction melt bonding. In the example of FIG. 2, the thickness **E62** of the batten, measured between the free face **62** and the support face **60**, is 4 mm. In practice, the thickness **E62** is equal to the distance **D34**, so that the face **62** is coplanar with the central portion **38** of the upper face **26**.

Each longitudinal outer edge **66** is chamfered to accommodate a steel-to-steel weld **S'** to secure the respective batten **56** or **58** to the fixing surface **12**. The chamfer of the edge **66** is provided on the side of the free face **62** and has an angle $\alpha 66$ of 40° with respect to a plane that is orthogonal to the support face **60**. Each longitudinal batten **56** and **58** has a thickened portion **70** projecting from the free face **62** and extending from the chamfered longitudinal outer edge **66**. The presence of this thickened portion **70** ensures the strength and durability of the steel-to-steel welding. In the example of FIG. 2, the battens **56** and **58** have a thickness **E70** of 5 mm, measured between the thickened portion **70** of the free face **62** and the support face **60**.

The chamfer of the longitudinal outer edge **66** for the weld **S'** is located at a sufficient distance away from the longitudinal edge **22** and therefore from the weld **S**, in order to avoid harmful heating which would adversely affect the mechanical strength of this weld **S**, and, in particular, to avoid any risk of delamination of the latter. This distance ensures the strength and durability of the weld **S**. For the sake of clarity, the steel-to-steel weld beads **S'** are only shown in FIG. 1.

Alternatively, the battens **56**, **58** need not be fixed to the surface **12** by welding, but rather secured by any other suitable means, for example riveting. In this case, the shape of the truss **10** is modified to receive the rivets.

Each longitudinal inner edge **64** is also chamfered in order to form a V-shaped groove with the adjacent chamfer **36** or **42**. The inclination of the chamfer **64** is equal to that of the

adjacent chamfers 36 or 42. The V-shaped groove thus formed is filled with a sealing gasket G that is only represented in FIG. 1 (for the clarity of the drawing) in the form of a filler to ensure the sealing of the friction melt bonding S.

Alternatively, the floor 2 is not obtained by extrusion but by another manufacturing method, as are also the truss 10 and the support element 110.

Alternatively, only one of the battens 56 or 58 is fixed to the floor 2 by means of friction melt bonding S, wherein the other battens are fixed by another suitable method, such as riveting.

A body structure 101 according to the second embodiment of the invention shown in FIG. 3 is described below.

This body structure 101 has similar characteristics with the body structure 1 of FIGS. 1 and 2. The description which follows is therefore centered on the differences between this second embodiment of FIG. 3 and the first embodiment of FIGS. 1 and 2. In particular, the reference numerals of FIG. 3, which are common to those of FIGS. 1 and 2, refer to the same features and objects which have been described above for the first embodiment where these characteristics and objects are found in the second embodiment.

The body structure 101 of FIG. 3 comprises a floor 2 identical to that described above, a longitudinal batten 156 and a frame 106, which differ from the battens 56 and 58 and the frame 6 described above in that the longitudinal batten 156 is integral with a support element 110 of the frame 6 and thus belongs to this support element 110. As a result, the floor 2 is directly fixed on the support element 110 by means of a friction melt bonding S, wherein the support member 110 comprises a portion in the form of a longitudinal batten 156.

The longitudinal batten 156 has a free face 62 with a thickened portion 70, an outer edge 66 and a support face 60 similar to those of the first embodiment of FIGS. 1 and 2. The friction melt bonding S of the batten 156 on the floor 2 may therefore be carried out in the same way with a similar tool as that used for the batten 56 on the floor 2 of the first embodiment.

The outer edge 66 is optionally welded or attached to a support member (not shown) of the steel alloy of the frame 106.

The longitudinal batten 156 is extended from a longitudinal edge 164 of the free face 62 lying opposite to the outer edge 66, by the support member 110, which protrudes upwards from the free face.

Alternatively, the floor 2 may be replaced by any aluminum alloy equipment element of the structure 1, wherein the truss 10 and the support element 110 are replaceable by any steel alloy support element of the structure body structure. For example, the aluminum alloy equipment element may be a cover belonging to structure 1, or an intermediate floor to form an intermediate level in the case of a multi-level floor structure.

Furthermore, the steel alloy support member may be formed by a steel alloy cover, a steel alloy floor, or a steel alloy deck. Alternatively, the equipment element may be secured to the support member with a single batten 56 or 58 and a single friction melt bonding S.

The various embodiments and variants described above may be combined to create new embodiments.

The invention claimed is:

1. A body structure for a railway vehicle, the body structure comprising:

a frame, which comprises at least one support element made at least predominantly of steel alloy;

5 at least one equipment element, made at least predominantly of aluminum alloy, and comprising at least a first plate comprising at least one longitudinal edge and a first face delimited by the longitudinal edge; and at least one longitudinal steel batten which is integral with the support element,

10 wherein the longitudinal batten is fixed flat on the first face by means of friction melt bonding, a support face of the batten being fixed to the first face, and

wherein the longitudinal batten has a longitudinal outer edge by means of which the longitudinal batten is welded on the support element, the longitudinal batten having a thickened portion extending from the longitudinal outer edge and projecting from a free face, opposite to the first face, and the outer edge having a welding chamfer.

15 2. The body according to claim 1, wherein a longitudinal flat spot is provided in the first face on only part of this first face extending from the longitudinal edge, wherein the longitudinal batten is fixed flat against the longitudinal flat spot.

20 3. The body according to claim 1,

wherein the first plate is one of two plates are provided, the first plate having a second face opposite the first face, and a second plate of the two plates being parallel to the first plate,

25 wherein the equipment element comprises a longitudinal web which protrudes from a lateral portion of the second face,

30 wherein the lateral portion extends from the longitudinal edge with respect to the longitudinal batten, and wherein the web connects the first plate to the second plate.

35 4. The body according to claim 1, wherein the longitudinal batten is integral with, and belongs to, the support element.

40 5. The body according to claim 1, wherein the longitudinal batten has a chamfered longitudinal internal edge, and

45 wherein the body structure comprises a sealing gasket applied against the longitudinal internal edge.

6. The body according to claim 1,

50 wherein the support element forms a truss, and wherein the equipment element forms a floor.

7. A method of manufacturing a body structure according to claim 1, the method comprising a step of fixing the longitudinal batten on the first face by means of friction melt bonding through the longitudinal batten by applying a rotating friction melt bonding tool to a free face of the longitudinal batten,

55 wherein the free face lies opposite a support face of the longitudinal batten against the first face.

8. The method according to claim 7, wherein the friction melt bonding tool is applied to the free face, the melt bonding tool facing the first face beyond the longitudinal edge.
